DISPENSING APPARATUS FOR CARBONATED BOTTLED LIQUIDS

Filed June 23, 1933

UNITED STATES PATENT OFFICE

2,070,488

DISPENSING APPARATUS FOR CARBONATED BOTTLED LIQUIDS

Robert D. McIntosh, River Forest, Ill., assignor to The Imperial Brass Manufacturing Company, Chicago, Ill., a corporation of Illinois

Application June 23, 1933, Serial No. 677,290

8 Claims. (Cl. 225—22)

My invention is concerned with dispensing apparatus for carbonated bottled liquids, and is designed to produce a device of the class described that can be cheaply manufactured, and that will be certain and efficient in its operation.

To illustrate my invention, I have annexed hereto a sheet of drawings, in which the same reference characters are used to designate identical parts in all the figures, of which,

Fig. 1 is a central vertical section of the complete apparatus;

Fig. 2 is a top plan view; and

Figs. 3, 4, and 5 are perspective views, in central vertical section, of the portions of the mechanism molded into the hard-rubber or similar base.

In carrying out my invention in its preferred form, I mold a preferably circular, bakelite base 10, which has at the center thereof and projecting upwardly therefrom the annular flange 11 forming a cup. In a downwardly projecting boss 12 at the center thereof, I imbed, when it is molded, a metallic, preferably brass, plug 13, which has the top portion 14 preferably hexagonal in cross section, and with it and its lower portion internally threaded, as shown. In one side thereof is a circular aperture 15 in which fits the reduced end 16 of a horizontal tube 17 molded into the base and occupying the generally circular rib 18 extending radially along the under side of the base. The other reduced end 18 of the tube 17 fits in a circular recess 19 formed in the plug 20, likewise molded in the base, and having its central hexagonal portion 21 flush with the top of the base. The lower portion of the plug has the bore 22 therein, so that the top of the plug 13 is connected through the tube 17 with the top of the plug 20, which top has the beveled portion 23 producing a concavity 24 which furnishes a seat for the rounded end 24 of the connecting piece 25, which has an annular shoulder 26 to co-operate with the internally flanged, hexagonal nut 27, which is screwed down on the threaded upper portion of the plug 20 so that its internal flange engages the flange 26 and secures the connecting piece 25 firmly in place. In this connecting piece 25, there is placed the vertical delivery tube 28, which has threaded on its upper end the valve member 29, which has a valve seat 30 therein with which operates the valve 31 secured on the end of the vertically reciprocating valve stem 32, which has the push button 33 threaded on its upper end. A helically-coiled, expanding spring 34 secured in the enlarged upper end of the passage through

the valve member 29 engages the button 33 to hold the valve seated, and also engages the annular disk 35, which presses down on the packing 36 beneath it so as to prevent leakage. A spout member 37 extends from the central portion of the casting and has the outlet passage 38 therein leading to the discharge nipple 39 through which the liquid is delivered.

The plug 13 has at its upper end the small enlargement 40 of the bore, which enlargement 10 furnishes the sharp edge 41 to co-operate with the tapered portion 42 of the piercing member 43, which has its threaded lower end 44 screwed into the threaded upper end of the plug 13. Above the enlarged central portion of the piercing member 43 extends the spear head 45 shaped to puncture the tin cap of a bottle as it is thrust downwardly thereon. A passage 46 for the liquid extends upwardly through the piercing member to near its top, and an outlet for the same is formed 15 by the two vertical slots 47 in the sides thereof above the annular seat 48 formed thereon. Above this seat is a small annular flange 49 which engages the internally projecting annular flange 50 formed in the bottom opening of 25 the soft-rubber, hollow ball 51, the downwardly projecting annular bottom portion 52 of which rests on the hexagonal portion 21 of the plug 20. The ball 51 has the opening 53 in the top, through which extends the point of the cap-piercing 30 member 43, and the material of the ball is preferably thinned out somewhat at the top so that, when a bottle is thrust downwardly thereon and the metallic cap is pierced, a liquid-tight connection will be maintained as long as the bottle 35 is held in its downward position. The hollow space in the ball 51 enables the pressure of the liquid reacting against the interior of the ball to increase the effective pressure of its sealing 40 surface against the bottle cap.

For this purpose, I provide on the top of the ring or cup 11 holding mechanism as follows: On the top of the cup are three equi-distant lugs 54 having small internally-threaded brass tubes 55 molded therein, and between these lugs are three 45 other equi-distant retaining lugs 56. Secured on top of the cup 11 by three screws 57 passed through the horizontal annular flanged bottom 58 thereof is the guiding sleeve 59. In the space between the flange 59 and the top of the cup 11 is 50 placed the retaining spring 60, which, as best seen in Fig. 2, is made of a single piece of wire having the generally circular finger pieces 61 at the ends thereof, and the body portion of which is triangular, with the pair of curves 62 therein to pass 55

around and engage two of the lugs 56. Three portions 63 of the wire, as seen in Fig. 2, extend inside of the guiding sleeve 59, so that when a bottle is thrust downwardly thereinto, the neck, 5 guided thereby, will bring the cap over the center of the piercing element, and the flange on the neck of the bottle will catch beneath the portions 63, which are spread apart in passing, and hold the bottle down. In this position, the piercing member is inside of the bottle, and the pressure 10 of the gas in the bottle will force the liquid therein through the slots 47 and the passage 46 and the tube 17, and so on, up through the tube 28 to the valve 31, so that it can be delivered from the 15 nozzle 39 merely by pressing the button 33 to open the valve.

While I have shown and described my invention as embodied in the form which I at present consider best adapted to carry out its purposes, it 20 will be understood that it is capable of modification, and that I do not desire to be limited in the interpretation of the following claims except as may be necessitated by the state of the prior art.

What I claim as new, and desire to secure by 25 Letters Patent of the United States, is:

1. In a device of the class described, the combination with a molded base having two metallic plugs imbedded therein connected by a metal tube, one plug being in the center and the other near 30 the circumference of means connected with an opening into one plug for puncturing a bottle cap and draining the contents of the bottle, a delivery tube connected with the other plug, and a valve in said tube near its outlet.

35 2. In a device of the class described, the combination with a molded base having two metallic plugs imbedded therein connected by a metal tube, one plug being in the center and the other near the circumference of means connected with 40 and opening into one plug for puncturing a bottle cap and draining the contents of the bottle, a delivery tube connected with the other plug, the open end of the bottle-receiving plug being flush with the top of the base, and a valve in said tube 45 near its outlet.

3. In a device of the class described, the combination with a molded base having two metallic plugs imbedded therein connected by a metal tube, one plug being in the center and the other near 50 the circumference of means connected with and opening into one plug for puncturing a bottle cap and draining the contents of the bottle, and a valve-controlled delivery tube connected with the other plug, the delivery tube having a rounded end 55 adapted to be seated in the concaved top of its plug, and held in place by a flanged nut screwed on the plug.

4. In a device of the class described, the combination with a molded base having two metallic plugs imbedded therein connected by a metal tube, one plug being in the center and the other 60 near the circumference of means connected with

and opening into one plug for puncturing a bottle cap and draining the contents of the bottle, and a valve-controlled delivery tube connected with the other plug, the bottle-receiving plug having its open threaded end provided with an edge 5 co-operating with the tapered surface of the cap-piercing element screwed therein.

5. In a device of the class described, the combination with a molded base having two metallic plugs imbedded therein connected by a metal 10 tube, one plug being in the center and the other near the circumference of means connected with and opening into one plug for puncturing a bottle cap and draining the contents of the bottle, and a valve-controlled delivery tube connected with 15 the other plug, the delivery tube having a rounded end adapted to be seated in the concave top of its plug and held in place by a flanged nut screwed on the plug, and the bottle-receiving plug having its open threaded end provided with an edge co- 20 operated with the tapered surface of the cap-piercing element screwed therein.

6. In a device of the class described, the combination with a molded base having two metallic plugs imbedded therein connected by a metal 25 tube, one plug being in the center and the other near the circumference and an annular flange projecting upward therefrom and concentric with the innermost plug, of means connected with and opening into the innermost plug for puncturing 30 a bottle cap and draining the contents of the bottle, a valve-controlled delivery tube connected with the other plug, and means on the annular flange for holding a bottle therein.

7. In a device of the class described, the combination with a molded base having two plugs therein connected by a tube and an annular flange projecting upward therefrom and concentric with the innermost plug and having lugs on its top 35 with threads therein, of means connected with and opening into the innermost plug for puncturing a bottle cap and draining the contents of the bottle, a valve-controlled delivery tube connected with the other plug, and means on the annular flange for holding a bottle therein including a 40 guiding sleeve secured thereon by screws in said lugs.

8. In a device of the class described, the combination with a molded base having two plugs therein connected by a tube and an annular flange 45 projecting upward therefrom and concentric with the innermost plug and having lugs on its top with threads therein and other retaining lugs in the same plane, of means connected with and opening into the innermost plug for puncturing 55 a bottle cap and draining the contents of the bottle, a valve-controlled delivery tube connected with the other plug, and means on the annular flange for holding a bottle therein including a guiding sleeve secured thereon by screws in said 60 lugs.

ROBERT D. MCINTOSH.
